SHUTTLE

Carl P. Park, Manchester, N. H., assignor to
U S Bobbin & Shuttle Company, Manchester,
N. H., a corporation of Rhode Island

Application September 19, 1936, Serial No. 101,630

10 Claims. (Cl. 139—223)

This invention pertains to weaving shuttles and relates more particularly to improved guiding and tensioning means for a shuttle of the self-threading type.

- 5 Uniformity of yarn tension is a very important desideratum for perfect weaving, but has been very difficult of attainment, at least without serious interference with easy and automatic threading, and particularly when weaving wiry 10 yarn or yarn which readily strands or separates into a plurality of filaments, both of which characteristics are common to yarns of the cellulose derivative type, for example, the yarn commonly known as "rayon".
- 15 A further difficulty experienced in weaving wiry or hard-twisted yarn by the use of a self-threading shuttle results from the tendency of such yarn to kink adjacent to the delivery eye of the shuttle, and in so kinking to twist and writhe in such a way as to escape from the shuttle eye.

Principal objects of the present invention are to provide self-threading tensioning and guiding means capable of exerting a substantially uniform and predetermined tension upon the yarn during both forward and reverse picks of the shuttle; to provide ready and accurate means for adjusting the degree of tension imposed upon the yarn and for maintaining the selected tension indefinitely; to provide tension means such that easy and certain self-threading is assured; to provide a delivery eye and associated parts such as to insure accurate entry of the yarn into the delivery grooves in the outer surface of the shuttle; to provide a wear-resistant delivery eye readily capable of replacement if broken or worn; and to provide improved means for securing the yarn guiding and tensioning block in the shuttle body without danger of affecting the predetermined yarn tension.

Other objects and advantages of the invention will be made manifest in the following more detailed description and by reference to the accompanying drawing, wherein:

- 45 Fig. 1 is a fragmentary front side elevation of a weaving shuttle equipped with the improved guiding and tensioning means,—the shuttle being viewed from the side at which the delivery eye is located;
- 50 Fig. 2 is a fragmentary plan view of the parts shown in Fig. 1;

Fig. 3 is a plan view of the improved yarn guide block removed from the shuttle body;

Fig. 4 is a side elevation of the block shown in Fig. 3;

Fig. 5 is an elevation of the tensioning block viewed from its forward end;

Fig. 6 is a fragmentary plan view substantially on the line 6—6 of Fig. 5 and indicating 60 the path of the yarn in broken lines;

Fig. 7 is a fragmentary section on the line 7—7 of Fig. 4;

Fig. 8 is a section, to larger scale, on the line 8—8 of Fig. 4;

Figs. 9, 10, and 11 are fragmentary side elevations of the tensioning block, to substantially the same scale as Fig. 8, illustrating various improved means for maintaining the adjustment of the tension;

Fig. 12 is an end elevation of the tensioning screw of the device of Fig. 11;

Fig. 13 is an end elevation illustrating the tensioning screw of the devices of Figs. 9 and 10;

Fig. 14 is a side elevation of the yarn guide eye piece removed from the guide block;

Fig. 15 is a fragmentary horizontal section on the line 15—15 of Fig. 4; and

Fig. 16 is a fragmentary section through the shuttle, substantially on the line 16—16 of Fig. 1.

Referring to the drawing, the numeral 1 designates a weaving shuttle, of the type commonly used in automatic looms, provided at its front end with a metal tip 2 in the usual way. The shuttle body is provided with a chamber 3 (Fig. 2) for the reception of the bobbin 4,—such chamber having a forward extension 5 for the reception of the thread guide block 6. This block may be of metal or any other suitable material commonly employed for the purpose,—the present invention being particularly concerned with improvements in this block and associated parts.

The front face 7 of the shuttle body is provided with the usual longitudinally extending shallow thread groove 8 (Fig. 1), having a forward extension comprising the parts 9 and 9^a, 35 said extension of the groove intersecting a laterally directed portion 5^a of the chamber 5.

The block 6 has a substantially flat bottom surface 10 which normally seats upon the floor of the chamber 5 of the shuttle body, such block having the spaced side walls 11 and 12 (Fig. 8) between which is a longitudinally extending portion 13 of the yarn guide passage. Near the entrance end of this passage a transverse pin or stud 14 extends from one wall to the other of the block. Preferably thus stud or pin is provided with an externally screw-threaded head 15 which engages a threaded bore in the side wall of the block (Fig. 8). This pin or stud 14 forms a support for a pair of tension plates 16 and 17 respectively, which are disposed face to face in a substantially vertical position, similarly to the tension plates disclosed in the patent to Co-misky No. 1,378,837, dated May 24, 1921, for example, said tension plates having openings 55 through which the stud 14 passes loosely. The upper ends of the plates 16 and 17 are bent outwardly substantially at right angles to the body portions of these plates, as shown at 16^a for example, and the outer end portions of these parts 60

5 ^{16a} are furnished with downwardly directed wings ^{16b} forming guide elements. These guide elements are arranged to slide loosely in wear-resistant bushings ^{17a} in openings in the side walls ¹¹ and ¹², respectively, of the block. The tension plates are thus free to move toward and from each other but at the same time are prevented from tilting excessively.

10 A coiled compression spring ¹⁹ bears against the left-hand surface (Fig. 8) of the plate ¹⁶, its outer end bearing against a screw-threaded stud ²⁰ received in an opening in the wall ¹¹ of the block. Preferably the spring ¹⁹ bears against the plate ¹⁶ at a point about midway of 15 the height of the latter, preferably slightly below where the projected axis of the bobbin would intersect the plate. A similar spring ²¹ bears against the right-hand or outer face of the plate ¹⁷ at a point opposite to the spring ¹⁹. The outer 20 end of the spring ²¹ is received in an axial pocket in a screw-threaded stud ²² engaging a screw-threaded opening in the wall ¹² of the block. Preferably this stud ²² is provided with a polygonal socket ²³ for the reception of a wrench by 25 means of which it may be turned, thereby to vary the resilient pressure exerted by the spring ²¹ against the plate ¹⁷, so as to adjust the tension upon the yarn which passes between the tension plates.

30 Preferably means is provided to retain the adjusting stud ²² in place after it has once been adjusted, so that the tension will not accidentally vary during the operation of the shuttle, in spite of the violent shocks to which the shuttle is subjected. For this purpose, as illustrated in Figs. 35 10 and 13, the screw-threaded peripheral surface of the stud ²² may be provided with flat surfaces or facets ²⁴, preferably disposed symmetrically, as shown in Fig. 13. In the arrangement 40 shown in Fig. 10, a flat bow spring ^{24a} is disposed within a horizontal bore ²⁵ in the thickness of the wall ¹² of the block, said bore intersecting the threaded opening which receives the stud ²², so that the central portion of the spring 45 ^{24a} resiliently bears upon the peripheral surface of the stud,—normally contacting one of the facets ²⁴ and thus holding the stud in adjusted position, although permitting it to be turned when sufficient force is applied by means of a wrench.

50 In Fig. 9 a slight modification is illustrated, wherein the spring ^{24a}, instead of being mounted in a bore in the block, is arranged in a horizontal slot or recess ^{25a} in the outer surface of the wall ¹² of the block.

55 A further modification of the tension-retaining means is illustrated in Figs. 11 and 12. In this instance the stud ^{22a} is furnished with spaced peripheral V notches ^{24b}, while the block is provided with a spring ²⁶ seated in a recess ²⁷ in the rear 60 edge of the wall ¹², the spring being fixed in position at its lower end and having a tooth member ²⁸ at its upper end which may engage any one of the notches ^{24b} of the stud, thereby to hold the stud in adjusted position.

65 The block is furnished with a substantially horizontal guide pin ²⁹ (Fig. 6) in the longitudinal portion ¹³ of the yarn passage and preferably at a point just forward of the tension plates ¹⁶ and ¹⁷, the pin ²⁹ being at such an elevation 70 that the projected axis of the bobbin lies substantially tangent to its upper surface. The block is also furnished with a substantially vertical guide pin ³⁰, which defines the junction between the longitudinal portion ¹³ of the thread passage and a transverse portion of said passage

which leads to the thread delivery eye. The pins ²⁹ and ³⁰ may be of porcelain or any other suitable wear-resistant material.

The block ⁶ has a lateral extension ^{6a} which is disposed in the extension ^{5a} of the chamber ⁵, such extension ^{6a} having an outer vertical face ^{6b} which is substantially flush with the forward face ⁷ of the shuttle body. This extension is furnished with a horizontal channel ³¹, whose upper and lower walls are substantially aligned 10 with the corresponding walls of the groove ⁹, ^{9a} of the shuttle body. The extension ^{6a} is provided with a vertical socket ^S (Fig. 15) which intersects the upper and lower walls of the channel ³¹, and which is designed to receive an eyepiece ³² (Fig. 7). This eyepiece (Fig. 14) may be of porcelain, hardened alloy steel, nitrided steel, or the like, of a wear-resistant character, and has the yarn delivery eye ³³, the axis of which is perpendicular to the axis of the shuttle and substantially tangent to that point of the guide post ³⁰ at which the yarn ^Y leaves said post on its way to the delivery eye. The eyepiece ³² has a lower surface ³⁴ (Fig. 14) which normally rests against the floor of the chamber ⁵ of the shuttle when the block ⁶ is positioned within the chamber ⁵. However, the eyepiece ³² is freely removable from the block ⁶ when the latter is removed from the shuttle, and thus the eyepiece may readily be replaced if worn or broken, or if it be desired to substitute a block of different material or one having a delivery eye of different size or shape.

The eyepiece is furnished with a substantially vertical threading slot ³⁵ at its lower part, one 35 side of said slot being defined by the curved horn-like portion ³⁶ of the eyepiece, such horn-like portion having an outer curved guiding face ³⁷. The parts are so dimensioned that when the eyepiece is disposed in the socket in the block, the 40 tip of the horn ³⁶ is disposed below the lower wall ³⁸ of the channel ³¹ (Fig. 4). As illustrated in Fig. 15, that part of the socket ^S which intersects the lower wall ³⁸ of channel ³¹, is beveled and widened at its forward end, as indicated at 45 ³⁹ in Fig. 15, so as to form a yarn-receiving clearance between the wall of the socket and the tip of horn ³⁶, thereby to permit the yarn, in following the curved surface ³¹, to snap beneath the tip of the horn and then to move up through the slot 50 ³⁵ into the eye ³³. However, it will be noted that when the thread has once entered the eye ³³, it is substantially impossible for it to escape from said eye by moving in a downward direction, since the lower wall surface ³⁸ of the channel ³¹ lies above the tip of the horn, and since there is no guide surface leading from the eye ³³ which would assist the yarn in moving downwardly and out from beneath the tip of the horn. Thus no matter how much the yarn may kink or 55 writhe during the operation of the shuttle, it is substantially impossible for it to escape from the shuttle eye, although, in threading, the yarn easily enters the eye.

The block ⁶ is provided with the usual forwardly directed guard member ⁴⁰ and with the beak ⁴¹ having the narrow tip ⁴² which underlies the guard ⁴⁰. The under surface of the beak ⁴¹ is smoothly finished and extends downwardly and laterally from the tip ⁴² toward the curved 70 guide surface ³⁷ of the eyepiece ³². As illustrated, this beak ⁴¹ is wholly devoid of any downwardly directed projections, horns or other elements to impede the yarn in its downward and lateral movement.

In threading, during the first pick of the shuttle, which is to the left, as viewed in Figs. 1 and 2, the yarn being held at its free extremity is drawn downwardly into the longitudinal portion 13 of the thread passage, it being noted that this slot is freely open throughout its length, and that the surfaces 44 and 45 at the opposite sides of this slot are smoothly sloped so as to guide the yarn toward the open entrance to the passage as it is drawn taut lengthwise of the shuttle. It may further be noted that the entrance of the yarn between the tension plates 16 and 17 is facilitated by the outward curvature of these plates where they merge with the parts 16^a so that upon this first pick the yarn is with certainty laid into the longitudinal portion of the passage and enters between the tension plates, where it is supported by the guide pin 29. Normally, near the end of this pick, the yarn snaps down beneath the guard 40 and under the tip 42 of the beak 41. Upon the second pick, when the shuttle moves to the right (as viewed in Figs. 1 and 2) the yarn swings laterally and slides easily down along the under surface 43 of the beak, and, meeting no obstruction whatever, quickly contacts with the outer curved surface of the horn 37 and is guided by the latter so as to pass the tip of the horn and enter the slot 35 and the eye 33, being now drawn around the post 30.

Since the axis of the guide eye 33 is substantially tangent to that point of the post 30 at which the yarn leaves the latter, and is also perpendicular to the axis of the shuttle, and since the axis of the guide eye 33 is also substantially midway between the upper and lower walls of the channel 31, it is evident that as the shuttle is picked back and forth, the yarn which emerges from the guide eye leads away from the shuttle at the same angle whether the shuttle be moving in one direction or the other. Thus the tension devices encounter substantially the same resistance to movement of the yarn, whether the shuttle be moving in one direction or the other, and thus it is possible to obtain a more constant tension and more even weaving than is usually the case.

In order to hold the block 6 in position, but without affecting the tension after the latter has once been adjusted, it is preferred to employ the arrangement illustrated in Fig. 16. As thus shown, the block 6 is furnished with a transverse screw-threaded opening for the reception of the screw-threaded shank portion 46 of a retaining screw having a screw-threaded head portion 47 of larger diameter than the shank portion 46 but preferably threaded with the same pitch thread as the latter. This threaded head portion 47 engages a screw-threaded bore in the body 1 of the shuttle, but the opposite end 48 of the screw freely enters an unthreaded bore of the shuttle body. The screw is of a length less than the thickness of the shuttle so that the screw does not project through to the forward face of the shuttle. With this arrangement, no matter how hard the screw may be set up, it does not tend to draw together the side walls of the shuttle body and thereby pinch the guide block so as to change the setting of the tension devices carried by the latter. It has been found that in prior constructions, where the screw for holding the block in position extends all of the way through the shuttle body, and is provided with means such as a nut, for tightening it, the wood of the shuttle 75 is so squeezed against the guide block as to

change the setting of the tension. The present invention avoids any such action.

With my arrangement it is thus possible to adjust the tension very delicately, as by means of the screw-threaded stud 22, with the assurance that the tension thus once set will not be varied either by reason of the sharp blows and shocks to which the shuttle is subjected during use, or by any manipulations necessary for fixing the block within the shuttle body. It should further be noted that since the screw which holds the block in position does not extend through the forward face of the shuttle, the latter is left smooth and unbroken and there is no danger that the yarn will be caught or abraded by contact with the end of the screw or by rubbing across the end of an open bore in the shuttle body.

In practice it has been found that the improved guide block with its associated parts permits yarn to be entered into the delivery eye with the greatest ease and certainty so that proper threading of the shuttle is substantially assured after the second pick. It has further been found that with this arrangement rayon or similar yarns of a very slippery and wiry nature, may readily be woven and the tension maintained very accurately even without recourse to the fur tension which has commonly been thought necessary to use in weaving yarns of this character. It has further been found that even in weaving such wiry yarns as those above noted and which tend to kink and writhe in the shuttle eye, there is substantially no possibility of unthreading of the shuttle accidentally by reason of such action of the yarn, while, as above noted, the symmetrical delivery of the yarn to and from the shuttle eye assists in maintaining a uniform tension. Moreover, the eyepiece may easily be removed and replaced when desired merely by removing the block from the shuttle body,—permitting the eye 40 to drop from the block, and then reinserting the new eye from the bottom of the block, all without the necessity of using tools or special instruments designed for the purpose.

While certain desirable embodiments of the 45 invention have been illustrated by way of example, it is to be understood that the invention is not necessarily limited thereto, but that all equivalents are to be regarded as falling within the 50 purview of the invention as set forth in the appended claims.

I claim:

1. In combination with a weaving shuttle, a 55 yarn guide block seated in a chamber in the shuttle body, said guide block having therein a substantially horizontal yarn delivery channel in its outer face extending longitudinally of the shuttle and a removable eyepiece carried by the block and having therein a yarn delivery eye which opens outwardly into said channel, said 60 eyepiece having a threading slot leading to the eye, one wall of the threading slot being defined by a curved horn having an outer yarn guiding surface, the free end of the horn being disposed below the lower wall of the yarn delivery channel, thereby to prevent accidental escape of yarn 65 from the eye.

2. In combination with a weaving shuttle, a 70 yarn guide block seated in a chamber in the shuttle body, said guide block having therein a substantially horizontal yarn delivery channel, and an eyepiece carried by the block and having therein a yarn delivery eye which opens into said channel, said eyepiece having a threading slot leading upwardly to the eye, one wall of the 75

threading slot being defined by a curved yarn guiding horn having an outer curved surface, the free end of the horn dipping down into a cavity in the lower wall of said delivery channel and terminating below the plane of said wall, thereby to prevent accidental escape of yarn from the eye.

3. In combination with a weaving shuttle having a longitudinally extending yarn guide groove in its front face, a yarn guide block seated in a chamber in the shuttle body, said block having an outer surface substantially flush with the grooved face of the shuttle, said outer face of the block having therein a channel whose upper and lower walls are substantially aligned with the upper and lower walls respectively of the groove in the shuttle, and a yarn delivery eyepiece disposed within the block, said eyepiece having an eye whose axis is substantially midway between the upper and lower walls of said channel.

4. In combination with a weaving shuttle having a longitudinally extending yarn guide groove in its front face, a yarn guide block seated in a chamber in the shuttle body, said block having an outer surface substantially flush with the grooved face of the shuttle, said outer face of the block having therein a channel whose upper and lower walls are substantially aligned with the upper and lower walls respectively of the groove in the shuttle, and a removable eyepiece carried by the block, said eyepiece having therein a yarn delivery eye whose axis is substantially perpendicular to the axis of the shuttle.

5. In combination with a weaving shuttle having a longitudinally extending yarn guide groove in its front face, a yarn guide block seated in a chamber in the shuttle body, said block having an outer surface substantially flush with the grooved face of the shuttle, said outer face of the block having therein a channel whose upper and lower walls are substantially aligned with the upper and lower walls respectively of the groove in the shuttle, and an eyepiece seated in the block, said eyepiece having therein a delivery eye disposed with its axis substantially perpendicular to the grooved face of the shuttle, the eyepiece having a threading slot at its lower part, one side of said slot being defined by a horn whose free end is below the lower wall of the channel.

6. In combination with a weaving shuttle having a longitudinally extending yarn guide groove in its front face, a yarn guide block seated in a chamber in the shuttle body, said block having an outer surface substantially flush with the grooved face of the shuttle, said outer face of the block having therein a channel whose upper and lower walls are substantially aligned with the upper and lower walls respectively of the groove in the shuttle, the block also having a socket which intersects the bottom wall of said channel, and an eyepiece mounted in the block, said eyepiece having therein a delivery eye whose axis is intermediate the top and bottom walls of the channel, the lower portion of the eyepiece being disposed in the aforesaid socket, said eyepiece having a threading slot, one side of which is defined by a curved horn whose free end is disposed below the plane of the lower wall of the channel.

7. In combination with a weaving shuttle having a longitudinally extending yarn guide groove in its front face, a yarn guide block seated in a chamber in the shuttle body, said block having an outer surface substantially flush with the

grooved face of the shuttle, said outer face of the block having therein a channel whose upper and lower walls are substantially aligned with the upper and lower walls respectively of the groove in the shuttle, the block also having a substantially vertical socket which intersects both the upper and lower walls of the channel, and an eyepiece fitting within said socket, said eyepiece having therein a delivery eye provided with a threading slot whose entrance end is below the plane of the lower wall of the channel, the socket and eyepiece being so relatively designed and arranged as to provide a narrow space through which a yarn may reach the entrance to said slot, the eyepiece having an external guide surface shaped to direct the yarn into said space.

8. In combination with a weaving shuttle having a longitudinally extending yarn guide groove in its front face, a yarn guide block seated in a chamber in the shuttle body, said block having an outer surface substantially flush with the grooved face of the shuttle, said outer face of the block having therein a channel whose upper and lower walls are substantially aligned with the upper and lower walls respectively of the groove in the shuttle, the block also having a substantially vertical socket which intersects both the upper and lower walls of the channel, and which is open at the lower surface of the block, and an eyepiece removably fitting within said socket and having a yarn delivery eye whose axis is in a plane intermediate the top and bottom of said channel.

9. A self-threading shuttle of the kind wherein a yarn guide block is seated in a chamber in the shuttle body, said block having a yarn passage comprising a longitudinal portion and a transverse portion, the longitudinal portion being freely open at its top to receive the yarn, a guard member at the forward end of the block, and a beak having its tip underlying the guard member, said beak having a smooth under surface extending downwardly and laterally from its tip, characterized in having a removable eyepiece of wear-resistant material normally seated in a socket in the block, said eyepiece having a guide eye whose axis is substantially coincident with that of the transverse portion of the yarn passage and having a threading slot leading upwardly into the eye, and in having a guide surface forming a continuation of said under surface of the beak arranged to direct the yarn downwardly toward the entrance to the threading slot.

10. In combination in a self-threading shuttle, a yarn guide block seated in a chamber in the shuttle body, said block having a yarn passage including a longitudinal portion and a transverse portion, the block having an eyepiece receiving socket, a removable eyepiece of wear-resistant material normally seated in said socket, said eyepiece having a yarn delivery eye terminating the transverse portion of the passage, the eyepiece having a threading slot leading upwardly into the eye and also having a thread guiding horn provided with a curved surface leading toward the entrance of the threading slot, a guard member at the forward end of the block, and a beak having its tip underlying but spaced from the guard member to permit entry of the yarn between them, the beak being devoid of downwardly directed projections and having a smoothly curved, laterally extending under surface operative to guide the entering yarn into contact with the curved surface of the guiding horn of the eyepiece.
